CLAIM

The ornamental design for a surgical laparotomy pad, as shown and described.

DESCRIPTION

FIG. 1 is a perspective view of a surgical laparotomy pad showing my new design, it being understood that the pattern continues throughout the article.

FIG. 2 is a rear elevational view thereof.

FIG. 3 is a view of the left vertical edge of the laparotomy pad of FIG. 1.

FIG. 4 is a view of the right vertical edge of the laparotomy pad of FIG. 1.

FIG. 5 is a view of the top edge of the laparotomy pad of FIG. 1.

FIG. 6 is a view of the bottom edge of the laparotomy pad of FIG. 1.

FIG-1

FIG-2

FIG-3
